UNITED STATES PATENT OFFICE

96,329

DESIGN FOR A WHEEL DISK OR SIMILAR ARTICLE

George Albert Lyon, Allenhurst, N. J.

Application December 22, 1934, Serial No. 54,542

Term of patent 14 years

To all whom it may concern:

Be it known that I, George Albert Lyon, a citizen of the United States and a resident of the city of Allenhurst, in the county of Monmouth and State of New Jersey, have invented a new, original, and ornamental Design for a Wheel Disk or Similar Article, of which the following is the specification, reference being had to the accompanying drawing, forming a part thereof.

On the drawing:

Figure 1 is an outer side view of a wheel disk embodying my design.

Figure 2 is a side elevational view of the disk shown in Figure 1, partly in section so as to show the contour of the outer portion of the disk on the line 2—2 of Figure 1.

Figure 3 is a profile view showing in outline form the contour of my novel design of disk.

I claim:

The ornamental design for a wheel disk or similar article, as shown.

GEORGE ALBERT LYON.
